X-RAY TUBE

Zed J. Atlee, Elmhurst, Ill., assignor to General Electric X-Ray Corporation, Chicago, Ill., a corporation of New York

Application May 3, 1941, Serial No. 391,679

8 Claims. (Cl. 250—142)

My invention relates in general to electronics and has more particular reference to the provision of an improved X-ray generator.

An important object of the present invention is to provide an X-ray tube having an envelope structure which is substantially immune to deterioration as a result of X-ray action; a further object being to eliminate X-ray tube failure as a result of envelope deterioration due to X-ray action on the envelope.

Another important object of the invention is to provide an envelope construction in X-ray tubes in which the absorption of useful X-rays by the envelope is reduced to an inconsequential minimum.

Another important object is to form the envelope principally of metal; a further object being to apply preferably metal tubing as an envelope in X-ray generators, so that the envelope may comprise substantially non-deteriorating material wherever exposed to the direct action of X-rays.

Another important object is to provide an X-ray tube having a principally metal envelope, thereby avoiding change in envelope voltage gradient characteristics of the tube due to envelope deposits resulting from filament or target evaporation during the service life of the tube; a further object being to eliminate the difficulties resulting from etching of glass envelopes in X-ray tubes by forming the envelope of metal at the zones where etching occurs, thereby preventing the development of cracks and eliminating the possibility of developing a gassy tube in service through localized heating of the envelope as a result of etching.

A further object is to provide an X-ray tube having an envelope comprising a preferably seamless steel tube within which all of the elements of the X-ray generator, including glass end seals, are enclosed, to the end that, by grounding the steel tube, the entire device may be rendered absolutely shock-proof; a further object being to arrange the elements of the generator within the tubular envelope portion in such a way that the glass end seals are absolutely protected against metallic deposit thereon through electrode evaporation during the service life of the tube, the glass end seals being furthermore protected against direct action of X-rays.

Another important object is to provide an X-ray tube in which the anode and cathode electrodes are supported in place on glass end seals,

the structure being arranged so that the glass seals carry extremely small mechanical loads.

Another important object is to provide an X-ray tube embodying a preferably sleeve-like metal envelope member in which is disposed anode and cathode electrodes supported in place on glass end seals, in turn carried in rims sealed to the opposite ends of the metal sleeve member so that the tube can be readily constructed by pre-fabricating the electrodes on the end seals, assembling the same in the tube and soldering the tube ends on the seal-carrying rings, while simultaneously degassing and evacuating the generator.

15 Among the numerous other important objects and advantages of the invention is to provide an extremely simple and inexpensive X-ray generator well adapted to mass production practices and embodying a substantially all-metal construction having the advantage of manufacturing accuracy inherent to machine finished metal parts.

20 These and numerous other important objects, advantages, and inherent functions of the invention will become apparent as the invention is more fully understood from the following description, which, taken in conjunction with the accompanying drawing, discloses a preferred embodiment of the invention.

25 Referring to the drawing:

Figure 1 is a sectional view illustrating an X-ray generator embodying the features of my present invention, the generator being shown in mounted position on supports, in accordance with the teachings of the invention; and

30 Figure 2 is a sectional view taken substantially along the lines 2—2 in Figure 1.

To illustrate the invention, I have shown on the drawing an X-ray tube 11 comprising an anode 13 and an opposed cathode 15 enclosed in a sealed envelope preferably comprising a seamless steel tube 11.

The anode 13 comprises a head supporting a target 19 in position opposite the cathode to receive the impingement of electrons emitted by the cathode during the operation of the device as an X-ray generator. The head of the anode is supported on a stem 21 which forms an annular seat 23. The cathode 15 also comprises a head 24 which may be mounted a filamentary element 24 which, when energized, forms a source of electrons for impingement upon the anode target 19. The head of the cathode is carried on a stem 25 which is formed with a shoulder defining a seat 27. The seats 23 and 27, respectively, on the

anode stem 21 and the cathode stem 25 each carry a cup-shaped metallic seal element 29. These elements 29 are formed with openings at one end to snugly receive the seats 23 and 27, the members being hermetically sealed on said seats, as by soldering. The members 29 extend from the seats 23 and 27 and form skirts embracing the stems 21 and 25, respectively, said skirts forming annular edges adapted to make glass-to-metal seals 31 with glass end seals 33. Each seal 33 comprises a glass disk having a central neck forming the seal 31 with the associated member 29, and a marginal flange forming a glass-to-metal seal 35 with one end of a rim 37, the other end of which is hermetically sealed on an annular ring member 39. The anode and cathode electrodes 13 and 15 are thus each supported on a ring member 39 and, for manufacturing convenience, the anode and cathode may be assembled on the rings 39 as assembly units. Each ring 39, outwardly of the rim 37 attached thereon, is formed with an annular groove 41 configurated to receive an end of the tube 17, so that merely by assembling the anode and cathode assembly units on the opposite ends of the tube 17, the generator may be finished to complete form by silver soldering the ends of the tube 17 in place in the grooves 41, the silver soldered joints being shown at 43.

It should be understood that X-ray generators function to produce X-rays in response to the activation of the anode by electronic action established by the operation of the cathode 15, said electronic action consisting of the impingement of electrons emitted by the cathode upon the anode target 19. Electronic impingement on the target results in generation of relatively large quantities of heat at the target, which is dissipated thence through the body of the anode, including the stem 21, which may carry heat dissipating means, such as fins 45, thereon outwardly of the envelope. Heat generated at the cathode likewise may be dissipated thence through the stem 25 outwardly of the envelope, the stems 21 and 25 extending each in a chamber 47 opening outwardly of the sealed envelope at the opposite ends thereof.

Electrons emitted by the element 24 pass outwardly thereof in straight paths toward the anode, but it will be noted that the body of the anode 13 is formed and arranged in position to shield the anode seal 33 from direct electron impingement. The cathode seal 33 likewise is shaded or shielded by the structure and arrangement of the cathode from direct impingement by X-rays emanating from the target 19 as a result of activation thereof by electron impingement thereon. The glass seals 33 thus are protected against deterioration as a result of X-ray or electron bombardment.

It should be understood also that X-ray generators are conditioned for operation by exhausting from the envelope substantially all gaseous and other impurities by evacuating the envelope, as by means of a molecular exhaust pump, and finally sealing the envelope in evacuated condition.

The device of my present invention is particularly suited for the accomplishment of envelope evacuation during and as a part of the final manufacturing step of sealing the electrode support rings 39 to the opposite ends of the tube 17. To this end, the formation of the silver soldered joints 43 may be accomplished in vacuum by means of high frequency induction. By intro-

ducing the several parts of the generator into a suitable vacuum chamber, then assembling the parts and finally forming the joints 43 by high frequency inductive action, the generator may be fabricated in completely finished and evacuated condition. Of course, the tube is not necessarily assembled and evacuated in the manner described, but the parts may be assembled and the joints 43 formed under ordinary atmospheric conditions and the tube evacuated by attachment with a molecular pump through a glass conduit connected in one of the glass seals 33, the connection being sealed off, as at 49, after the tube has been evacuated and otherwise conditioned for service.

It will be noted that the cathode comprises conductors 51 for supplying energy to the filamentary element of the cathode, and a conductor 53 which is connected to one end of a gettering wire 55, the other end of which is electrically connected with the stem 25 preferably by connecting the wire 55 on the head of the cathode. By applying electrical potential between the conductor 53 and the stem 25 outwardly of the seal, the gettering wire 55 may be actuated to perform a gettering operation within the envelope of the generator. Upon the completion of the gettering operation, the conductor 53 may be electrically connected to the stem 25, as by tying the parts together as shown. The conductors 51 and 53 extend through insulated seals 57 formed in the support member 27 of the cathode structure.

The tube, of course, may be mounted for operation in any suitable or convenient fashion, and the envelope 17 may be grounded to render the tube absolutely shock-proof. As shown, a pair of spaced pedestals 59 of insulating material may be provided, said pedestals each forming a socket 61 for the reception of high voltage cable terminals 63, the socket of each pedestal being provided with terminal prong receivers 65 in position to receive and make electrical contact with connector prongs 67 on the cable terminals 63 when the same are inserted in the sockets 61. The pedestals 59 are formed with annular seats 69 in position to receive the rings 39 of the tube, which may be secured to the pedestals in position therebetween by fastening bolts 71 extending in openings in the rings 39 and threading in sockets formed in the pedestals 59 at the seats 69. The outer surfaces of the pedestals 59 may be covered with a grounded metal sheath 73 which may be electrically connected with the metal tube envelope as a result of the clamping of the rings 39 on the seats 69, thereby rendering the entire assembly shockproof.

The surface of each pedestal 59 within the annular seat 69 is preferably formed with an annular groove 75 and an annular rib 77 inwardly of the groove 75, said rib enclosing a seat 79.

The pedestal supporting the anode end of the generator carries a contact prong 81 mounted at one end in the pedestal at the seat 79, said prong 81 extending outwardly in position to engage in a socket 83 formed in the anode stem 21. The prong 81 thus may form electrical contact with the stem 21 as a result of the mounting of the tube on the pedestal. The pedestal mounted end of the prong 81 in turn is electrically connected with the prong receivers 65 by means of a conductor 85 extending in the insulating material of which the pedestal is formed.

The pedestal supporting the cathode end of the generator also carries means for facilitating elec-

trical connection of the stem 25 and the conductors 51 with the prong receivers 65. To this end, the seat 79 is fitted with friction plug members 87, which are electrically connected with the receivers 65 by conductors 89 extending in the insulating material of the pedestal. The stem 25 carries a support frame 91 of insulating material in which are fitted grommets 93, one of which is electrically connected with the stem 25 and the others of which are each electrically connected with one of the conductors 51. It will be seen that the support frame 91 carries the grommets 93 in position to fit upon the members 87 and to form electrical contact therewith as the ring 39 at the cathode end of the tube is fastened on the seat 69 of the pedestal.

It will be noted that the chamber 47 defined by the end seals is closed by the pedestals 59 when the generator is in mounted position therebetween. Each pedestal may be formed with an inlet conduit 95 and an outlet conduit 97 through which cooling liquid from a source outwardly of the pedestal may be circulated into and out of the chamber 47 for the purpose of cooling the anode and cathode structures.

If desired, the preferably steel envelope 17 may be formed with a window opening 99 opposite the target 19, and a pane of material 101, which is substantially transparent to X-rays, may be sealed on the envelope at said opening. I prefer to utilize a beryllium window-pane 101, since beryllium has an exceedingly low X-ray absorbing characteristic. The beryllium pane may be applied by soldering it in a ring of cold rolled steel 103 by means of a suitable solder 105. In accordance with this invention, an alloy of a metal which has a tendency to form rapid solution with beryllium and a metal which has a tendency to form solution with beryllium less rapidly may be employed in order to form a vacuum-tight joint between beryllium and other metals as, for example, cold rolled steel. I prefer, therefore, to use a special soldering alloy comprising about 50% silver and 50% copper to form a vacuum-tight joint between the beryllium window-pane disk 101 and the preferably steel collar or bushing 103, the soldering or brazing operation being accomplished in a hydrogen furnace with calcium chloride as a flux. The silver-copper alloy has the property of wetting the beryllium but does not go fully into solution with the beryllium before a satisfactory joint is formed. In order that the alloy may flow evenly upon the beryllium member to form the joint, it should be in a highly molten state; but the higher the temperature, the faster is the rate at which beryllium will go into solution. Pure copper in the molten state goes rapidly into solution with beryllium, but silver, on the other hand, dissolves beryllium slowly, while alloys of copper and silver have intermediate rates of solution with beryllium. Furthermore, all alloys of copper and silver have melting temperatures lower than that of pure copper, and all alloys having less than 15% of copper have melting points lower than that of pure silver, for which reason silver-copper alloys have the added advantage that brazing therewith may be accomplished at low temperature, which additionally facilitates the control of the rate of beryllium solution. For the purposes of the present invention, it is preferable that the amount of copper in the copper-silver alloy be greater than the copper constituent in the eutectic alloy, which comprises 72% silver and 28% copper.

The thickness of the beryllium disk 101 may vary, but satisfactory results may be obtained by employing a disk having a thickness within the range $\frac{1}{2}$ to $\frac{1}{16}$ of an inch.

5 It will be understood, of course, that the invention is not necessarily limited to the use of silver-copper alloy, although it is preferable, for the purpose involved, that the alloy be one having a melting temperature within the range between 700° and 900° centigrade. Temperatures above 900° centigrade are undesirable because of the danger of cracking or checking parts of the generator and also because of the danger of dissolving the beryllium during the brazing 10 operation.

15 In practice, satisfactory brazing results have been obtained with an alloy comprising 80% copper, 15% nickel, and 5% iron, and I have also found that aluminum may be also employed 20 as a soldering agent for joining beryllium with other metals.

25 After the beryllium window 101 has been secured in the collar 103, the collar may be sealingly united with the envelope member 17 in any suitable or preferred fashion, since the parts 17 and 103 preferably both comprise steel.

30 It is thought that the invention and its attendant advantages will be fully understood from the foregoing description, and it is obvious 35 that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A device of the class described comprising a tubular metallic member forming an envelope, 40 re-entrant means extending within the tubular member at the opposite ends thereof, said re-entrant means forming mounting rims, an insulated electrode support carried by and annularly sealed to each mounted rim within said tubular member, and an electrode carried by and annularly sealed to each support within said tubular member whereby the electrodes, the insulated electrode supports, and said mounting rims are housed entirely within the tubular metallic member.

2. A device of the class described comprising a tubular metallic member forming an envelope, re-entrant means extending within the tubular member at the opposite ends thereof, said re-entrant means forming mounting rims, an insulated electrode support carried by and annularly sealed to each mounting rim within said tubular member, and an electrode carried by each support within said tubular member, each electrode comprising an annular mounting skirt annularly sealed to the support on which it is carried.

3. A device of the class described comprising a tubular metallic member forming an envelope, metallic re-entrant means extending within the tubular member at the opposite ends thereof, said re-entrant means forming mounting rims, an insulated electrode support carried by and annularly sealed to each mounting rim within said tubular member, each support comprising a glass member having an annular anchored edge making a glass-to-metal seal with the rim on which it is mounted and an annular electrode mounting edge, and an electrode carried by each support within said tubular member, each electrode comprising a mounting skirt providing an

annular edge forming a metal-to-glass seal with the mounting edge of the electrode support on which it is carried.

4. A device of the class described comprising a tubular metallic member forming an envelope, metallic re-entrant means extending within the tubular member at the opposite ends thereof, said re-entrant means forming mounting rims, an insulated electrode support carried by and annularly sealed to each mounting rim within said tubular member, each support comprising a glass member having an annular anchored edge making a glass-to-metal seal with the rim on which it is mounted and an annular electrode mounting edge, each glass member comprising a disk-like ring having inner and outer edges projecting oppositely therefrom to form said anchored and electrode mounting edges, and an electrode carried by each support within said tubular member, each electrode comprising a mounting skirt providing an annular edge forming a metal-to-glass seal with the electrode mounting edge of the glass member on which it is carried.

5. A device of the class described comprising a tubular metallic member forming an envelope, re-entrant means extending within the tubular member at the opposite ends thereof, said re-entrant means forming mounting rims within said tubular member, said tubular member having inwardly extending flange means at its opposite ends and said mounting rims being carried by and sealed to said flange means, an insulated electrode support carried by and annularly sealed to each mounting rim within said tubular member, and an electrode carried by and annularly sealed to each support within said tubular member whereby the electrodes, the insulated electrode supports, and said mounting rims are housed entirely within the tubular metallic member.

6. A device of the class described comprising a tubular metallic member forming an envelope, re-entrant means extending within the tubular member at the opposite ends thereof, said re-entrant means forming mounting rims, an annular flange ring sealed on the tubular member at each end thereof, said flange ring having an outwardly extending mounting portion and an inwardly extending support portion carrying one of said mounting rims within the tubular member and

annularly sealed thereon, an insulated electrode support carried by and annularly sealed to each mounting rim within said tubular member, and an electrode carried by and annularly sealed to each support within said tubular member whereby the electrodes, the insulated electrode supports, and said mounting rims are housed entirely within the tubular metallic member.

7. A device of the class described comprising 10 a tubular metallic member forming an envelope, metallic re-entrant means extending within the tubular member at the opposite ends thereof, said re-entrant means forming mounting rims, an annular flange ring sealed on the tubular member 15 at each end thereof, said flange ring having an outwardly extending mounting portion and an inwardly extending support portion carrying one of said mounting rims within the tubular member and annularly sealed thereon, an insulated 20 electrode support carried by and annularly sealed to each rim within said tubular member, each support comprising a glass member having an annular anchored edge making a glass-to-metal seal with the rim on which it is mounted and an 25 annular electrode mounting edge, each glass member comprising a disk-like ring having inner and outer edges projecting oppositely therefrom to form said anchored and electrode mounting edges, and an electrode carried by each 30 support within said tubular member, each electrode comprising a mounting skirt providing an annular edge forming a metal-to-glass seal with the electrode mounting edge of the glass member on which it is carried.

35 8. A device of the class described comprising a tubular metallic member forming an envelope, re-entrant means extending within the tubular member at the opposite ends thereof, said re-entrant means forming mounting rims, an insulated 40 electrode support carried by and annularly sealed to each mounting rim within said tubular member, and an electrode carried by and annularly sealed to each support within said tubular member under vacuum conditions whereby the 45 electrodes, the insulated electrode supports and said mounting rims are housed entirely within the tubular metallic member under vacuum conditions.

ZED J. ATLEE.
